UNITED STATES PATENT OFFICE.

EDWARD CHARLES HASEMANN, OF ORLANDO, FLORIDA.

REFLECTING LEVEL.

Application filed January 29, 1927. Serial No. 164,565.

This invention relates to levels such as are used by carpenters, masons and other workers and the general object of the invention is to provide means whereby the 5 bubble of the level may be seen from either side of the device when the level is disposed above the head of the person using it.

A further object is to provide a device of this character which may be readily installed in the ordinary stock of the level.

A still further object is to provide means whereby the bubble glass or glasses may be adjusted.

Other objects will appear in the course of 15 the following description.

My invention is illustrated in the accompanying drawings wherein:—

Figure 1 is a front elevation of a level stock with my improvement applied thereto;

20 Fig. 2 is a section on the line 2—2 of Figure 1;

Fig. 3 is a section on the line 3—3 of Figure 1;

25 Fig. 4 is a longitudinal section on the line 4—4 of Figure 1;

Fig. 5 is a perspective view of the support upon which the levels are mounted;

Fig. 6 is an enlarged fragmentary sectional view of the upper end of the frame 30 and mirrors.

Referring to these drawings 10 designates the stock of a level of any ordinary or usual character or any other device to be used in this manner. This stock is formed 35 with an opening 11 having a length preferably of about $3\frac{1}{2}$ " and a width of approximately 2". This opening extends inward somewhat beyond the middle plane of the stock and then the opening is formed of 40 less length so as to provide a shoulder 12. The margins of the opening may be recessed or rabbeted as at 13. Disposed within in the opening and resting against this shoulder is a web or plate of metal design- 45 nated 14, preferably I-shaped in cross section. This web is engaged against the shoulder 12 by means of screws 15 or other suitable fastening devices and the flanges 16 at the top and lower ends of the web 14

50 bear against the upper and lower faces of the cut out portion 11, as is evident from Figure 2.

Pivoted at one end upon the web 14 is a bubble containing trough 17 and disposed 55 on the other side of the web 14 and pivoted at its opposite end to the web 14 is the other

bubble containing trough 17^a. These troughs are alike and may have any suitable form in cross section but are so formed as to hold within them the bubble glasses 18 of 60 any ordinary or usual type. The free end of each trough 17 or 17^a is engaged by a screw 19 which extends upward through the stock and has its head 20 disposed upon the upper face of the stock and against the countersunk plate 21. A spring 22 surrounds the screw 19 and bears at its lower end against the bottom of the trough 17 or 17^a and at its upper end bears against the 65 top flange 16. It will be seen that the 70 spring exerts a constant downward pressure upon the free end of the trough and that by turning the screw in one direction or the other, the free end of the trough may be raised or lowered so as to adjust the bubble 75 glass to bring it exactly in its proper position.

Attached to the upper flange 16 and disposed one on each side of the web 14 is an angularly disposed reflector 23 preferably 80 of polished steel, though I do not wish to be limited to this. As illustrated, this reflector is mounted upon a supporting block or member 24 triangular in cross section to which the reflecting plate 23 is attached by 85 screws 25 or like means. This member 24 is attached to the upper flange 16 by means of screws 26. This member 24 holds the reflector 23 at a certain definite angle with 90 relation to the web 14 and at such a position that the image of the bubble in the glass 18 is reflected downward and outward, thus permitting a worker to use this level in positions above his head and permitting him to look upward into the reflector and 95 see the image of the bubble and thus know whether or not the bubble is in its zero or medial position. It will be seen that by providing two bubble glasses and two reflectors that the instrument may be used or observed 100 from either side.

Disposed within the recesses 13 is an aluminum plate 27 carrying a pane 28 of transparent material, such as glass, through which the bubble and the reflection of the 105 bubble may be observed. The bubble glass supporting member 14 and all other allied parts may be made of aluminum if desired or any other suitable material and while I have illustrated certain details of construction, I do not wish to be limited thereto except as defined in the appended claims.

The advantages of my invention will be obvious from what has gone before. The device may be readily applied to any ordinary stock. The level may be used as an ordinary level and in the usual manner but, as before stated, it is capable of being used with the level disposed above the head of the worker at any height as the bubble may be readily observed through the reflector.

10 By providing an adjusting means of the character stated, the bubble glass may be readily adjusted from time to time so as to make the instrument accurate. I do not wish to be limited, however, to the use of

15 the adjusting device.

I claim:—

1. A level comprising a stock, a supporting member mounted within the stock and having a medial web, a pair of bubble glasses disposed one on each side of the medial web and each pivoted at one end thereto for movement parallel to the plane of said web, means engaging the stock and the free end of each bubble glass whereby each bubble

25 glass may be adjusted, and a pair of reflectors mounted upon the supporting member above the bubble glasses, one on each side of the medial web and reflecting the images of the bubble glasses downward and

30 outward.

2. In a level, a stock having an opening therethrough, a supporting web having flanges at its upper and lower ends disposed within the opening and engaged with the stock, a pair of bubble glass supports, each pivoted at one end to said web, means engaging the free end of each support for vertically adjusting said support, bubble glasses mounted within the respective supports, and

35 mirrors carried by the upper flange of said web, one on each side thereof, each mirror being downwardly and inwardly inclined to

reflect an image of the corresponding bubble glass downward and outward.

3. A level including a stock having a transverse opening therein, an I-shaped supporting member mounted within the opening and including a medially disposed web and right angularly disposed flanges at the upper and lower margins of the web, a pair of oppositely disposed bubble glass troughs, each pivoted at one end to the web, bubble glasses mounted therein, screws passing downward through the stock and each engaging the free end of one trough, springs surrounding the screws and bearing against the free ends of the troughs and at their upper ends bearing against the upper flange of the web, triangular members mounted upon the upper flange of the web on each side of the web, reflectors carried by said triangular members and reflecting the image of the corresponding bubble glass downward and outward, and plates applied to the stock and extending across the opening therein and having transparent panes.

4. A level including a stock having a transverse opening therein, an I-shaped supporting member mounted within the opening and including a medially disposed web and right angularly disposed flanges at the upper and lower margins of the web, a pair of oppositely disposed bubble glasses disposed one on each side of the web, triangular members mounted upon the upper flange of the web, on each side of the web, reflectors carried by said triangular members and reflecting the image of the corresponding bubble glass downward and outward, and plates applied to the stock extending across the opening therein and having transparent panes.

In testimony whereof I hereunto affix my signature.

EDWARD CHARLES HASEMANN
